UNITED STATES PATENT OFFICE

131,595

DESIGN FOR A COMBINED AUTOMOBILE INSTRUMENT PANEL AND INTERIOR DOOR MOLDING

Samuel K. Wald, Detroit, Mich., assignor to
Chrysler Corporation, Highland Park, Mich., a
corporation of Delaware

Application January 22, 1941, Serial No. 98,276

Term of patent 7 years

To all whom it may concern:

Be it known that I, Samuel K. Wald, a citizen
of the United States, residing at 1191 Burlingame
Avenue, in the city of Detroit, county of Wayne,
and State of Michigan, have invented a new,
original, and ornamental Design for a Combined
Automobile Instrument Panel and Interior Door
Molding, of which the following is a specification,
reference being had to the accompanying drawing,
forming part thereof, in which:

Fig. 1 is a fragmentary, perspective view of the
instrument panel section and the right hand
door molding.

Fig. 2 is a fragmentary view showing the in-
strument panel and the left hand door molding.

Fig. 3 is a top plan view of the combined auto-
mobile instrument panel and interior door mold-
ing showing the complete article of my new de-
sign.

The dot-and-dash lines shown in Figs. 1 and
2 are for illustrative purposes only.

I claim:

The ornamental design for a combined auto-
mobile instrument panel and interior door mold-
ing, substantially as shown and described.

SAMUEL K. WALD.
